UNITED STATES PATENT OFFICE.

JOHN R. MICHAEL, OF ARAB, ALABAMA.

METAL PRESSING AND SHAPING TOOL.

Application filed April 15, 1924. Serial No. 706,787.

To all whom it may concern:

Be it known that I, JOHN R. MICHAEL, a citizen of the United States, residing at Arab, in the county of Marshall and State of Alabama, have invented certain new and useful Improvements in Metal Pressing and Shaping Tools; and I do hereby declare the following to be a full, clear, and exact description of the invention, such as will 10 enable others skilled in the art to which it appertains to make and use the same.

This invention provides a tool specially adapted for the use of a smith in the reshaping of plow and cultivator sweeps and 15 which is adjustable to insure proper setting of the eye and wings of the sweep whereby it will operate properly to shed the soil and trash and operate with a minimum resistance so as not to unnecessarily add to 20 the draft when plowing or cultivating.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without 25 departing from the spirit of the invention.

Referring to the accompanying drawings forming a part of the application:

Figure 1 is a side view of a metal pressing and shaping tool embodying the invention, 30 partly in section,

Figure 2 is a front view thereof,

Figure 3 is a horizontal sectional view on the line 3—3 of Figure 1,

Figure 4 is a horizontal sectional view on 35 the line 4—4 of Figure 1,

Figure 5 is a detail sectional view on the line 5—5 of Figure 3,

Figure 6 is a detail sectional view on the line 6—6 of Figure 3,

Figure 7 is a detail view of an adjusting pin and a portion of the anvil, the latter being shown in section,

Figure 8 is a view of an adjusting pin as seen from the lower end, and

Figure 9 is a detail view of the adjusting wedge.

Corresponding and like parts are referred

to in the following description and designated in the several views of the drawings by like reference characters.

55

The tool comprises a base 1 provided with depending lugs 2 which are apertured to receive bolts for securing the tool to a post or other suitable support. A base 3 is adapted to be bolted or otherwise secured to the base 1 and a post 4 rises from an end portion thereof and terminates at its upper end in an overhanging portion 5. A bed 6 projects forwardly from the foot of the post 4 and may form a part of the 60 base 3 or be bolted thereto and to the base 1 as found most advantageous. An anvil is mounted upon the bed 6 and comprises a body portion and a middle and side platens which are relatively adjustable to admit of 65 giving the required shape to the sweep. The anvil as a whole has the general outline of a plow sweep and comprises a middle and side portions. The middle and side portions of the body of the anvil are designated by 70 the numerals 7 and 8, respectively, and are fixed.

75

Hooked members 11 are mounted upon the outer ends of the side portions 8 of the body of the anvil and are adjustable by 80 means of set screws 13. Hooked members 12 are mounted upon the parts 8 of the anvil intermediate the ends thereof and are adjustable by means of set screws 14 and these hooked members and set screws provide for adjustment of the side wings of 85 the sweep when setting the tool to give the required shape to the sweep to be forged. The middle platen 9 is adjustable by means of a wedge 15 which is adapted to be set 90 by means of an adjusting screw 16. A pivot pin 17 connects the middle platen 9 to the middle portion 7 of the anvil body and a screw 18 coacts with a slotted post 19 to hold the platen 9 in the required adjusted 95 position. A pin 20 projects upwardly from the platen 9 to enter the eye of the sweep and maintain the shape thereof during the pressing or forging operation.

90

A plunger 21 cooperates with the anvil 100 and conforms approximately to the shape thereof. A link 22 is pivoted at its lower end to a stud of the plunger and is provided at its upper end with a strap 23 which

is fitted to an eccentric 24 which is adjustable to vary the effective leverage for operating the plunger. An operating lever has the eccentric 24 connected thereto and is pivoted to the overhanging portion 5 of the post 4. This operating lever comprises a handle 25 and a shank 26, the latter comprising side portions of metal between which the eccentric 24 and handle 25 are positioned. A pivot pin 27 connects the operating lever to the overhanging portion 5 of the post and the eccentric 24 is provided with a plurality of openings 28 at different distances from the center whereby the lever-
age may be adjusted as required.

Adjusting pins 29 coact with the anvil and their heads normally project above the side platens 10 and their side faces 30 are at different distances from the longitudinal 20 axis of the pins, and by setting the pins provision is had for adapting the anvil to sweeps having wings of different widths. When the sweeps have wide wings, the adjusting pins 29 may be removed.

25 Preliminary to shaping a sweep, the platen 9 of the anvil is adjusted so as to give the proper set to the eye and wings of the sweep and the latter is heated in a forge and placed upon the anvil and the 30 lever operated to lower the plunger, thereby causing the sweep to conform to the anvil, as will be readily understood. Links 31 connect the link 22 to the post 4, thereby causing the plunger to coact properly with the anvil during the pressing operation. 35 A bail 32 connected to the links 31 engages a rearward extension 33 on the plunger when it is in its lowermost position and assists in raising the plunger from the 40 sweep after the latter has been pressed.

What is claimed is:

45 1. A tool of the character specified for shaping plow and cultivator sweeps, the same comprising an anvil including adjustable middle and side portions, and a plunger in cooperative relation with the anvil.

50 2. A tool of the character specified for shaping plow and cultivator sweeps, the same comprising an anvil including a body and platens, the latter being adjustable relatively to the body, and a plunger in cooperative relation with the anvil.

55 3. A tool for shaping plow and cultivator sweeps, the same comprising an anvil including a middle and side portions, and means for independently adjusting the respective members, and a plunger in cooperative relation with the anvil.

60 4. A tool of the character specified comprising an anvil including a body portion and a middle and side platens, means for independently adjusting the several platens, and a plunger in cooperative relation with 65 the anvil.

5. In a tool of the character set forth, an anvil comprising a middle and side body portions and a middle and side platens, and independent adjusting means mounted upon the respective parts of the body and adapted to effect adjustment of the several platens. 70

6. In a tool for shaping plow and cultivator sweeps, an anvil comprising a body portion adapted to support the eye and 75 wing of a sweep, platens mounted upon the respective portions of the body, and means for independently adjusting the respective platens and securing the same in the required adjusted position. 80

7. A tool for shaping plow and cultivator sweeps, the same comprising an anvil body including a middle and side portions, platens mounted upon the respective parts of the body, and means mounted upon the 85 body portion of the anvil and adapted to effect independent adjustment of the respective platens.

8. In a tool for shaping plow and cultivator sweeps, and in combination with an 90 anvil adapted to receive the sweeps, adjusting pins mounted upon the anvil and comprising faces disposed at different distances from the center of the pin and adjustable to admit of the required stop face being 95 brought into operative position.

9. In a tool of the character specified, an anvil, a post at one side of the anvil, a plunger adapted to coact with the anvil, an operating lever mounted upon the post, an 100 eccentric link connection between the operating lever and plunger, a link connection between the post and plunger carrying link, and a bail carried by said link connection and adapted to coact with the plunger. 105

10. In a tool of the character specified, an anvil, a post at one side of the anvil, a plunger, an operating lever, an eccentric having adjustable connection with the operating lever and post whereby to vary the 110 effective leverage of the operating lever, and a link connection between said eccentric and plunger.

11. In a tool of the character specified, a plunger, an operating lever therefor, an 115 eccentric having adjustable connection with the operating lever and with a support whereby to vary the effective leverage of the operating lever, and a link connection between said eccentric and plunger. 120

12. A tool of the character specified comprising a base adapted to be secured to a suitable support, a post provided at its lower end with a base adapted to be secured to the supporting base and having an extension forming a bed, said post terminating at its upper end in an overhanging portion, an anvil body mounted upon said bed, a middle and side platens mounted upon corresponding portions of the anvil body, 125 130

means mounted upon the anvil body for adjusting the respective platens, a plunger, an operating lever mounted upon the overhanging portion of the post, an eccentric having adjustable connection with the operating lever and post, and a link connection between the eccentric and plunger.

In testimony whereof I affix my signature in presence of two witnesses.

JOHN R. MICHAEL.
